Primary Examiner — Jennifer Rivard

(74) *Attorney, Agent, or Firm* — Dorsey & Whitney LLP

(57) **CLAIM**

The ornamental design for luggage, as shown and described.

DESCRIPTION

FIG. 1 shows a front perspective view of luggage;
FIG. 2 shows a front elevation view of the luggage of FIG. 1;
FIG. 3 shows a rear elevation view of the luggage of FIG. 1;
FIG. 4 shows a left elevation view of the luggage of FIG. 1;
FIG. 5 shows a right elevation view of the luggage of FIG. 1;
FIG. 6 shows a top view of the luggage of FIG. 1; and,
FIG. 7 shows a bottom view of the luggage of FIG. 1.
The dashed lines in FIGS. 1-7 show the environment and
boundaries of the luggage and form no part of the claimed
invention.

1 Claim, 6 Drawing Sheets
